DESIGN FOR A COMBINED PEDESTAL CUSPIDOR AND TUMBLER HOLDER

Oscar H. Pieper and Alphonse F. Pieper,
Rochester, N. Y.

Application July 5, 1935, Serial No. 57,534

Term of patent 14 years

To all whom it may concern:

Be it known that we, Oscar H. Pieper and Alphonse F. Pieper, citizens of the United States, residing at Rochester, in the county of Monroe and State of New York, have invented a new, original, and ornamental Design for a Combined Pedestal Cuspidor and Tumbler Holder, of which the following is a specification, reference being had to the accompanying drawing, forming a part thereof.

In the drawing:—

We claim:—

The ornamental design for a combined pedestal cuspidor and tumbler holder, as shown.

In witness whereof, I hereunto subscribe my name this 1st day of July, 1935.

OSCAR H. PIEPER.

In witness whereof, I hereunto subscribe my name this 26th day of June, 1935.

ALPHONSE F. PIEPER.
